US00D956764S

(12) **United States Design Patent** (10) **Patent No.:** **US D956,764 S**
(45) **Date of Patent:** **** Jul. 5, 2022**

(54) **MOBILE DEVICE ACCESSORY**

- (71) Applicant: **Katana Safety, Inc.**, Greenville, SC (US)
(72) Inventor: **Todd W. Baldree**, Greer, SC (US)
(73) Assignee: **Katana Safety, Inc.**, Greenville, SC (US)

(**) Term: **15 Years**(21) Appl. No.: **29/715,115**(22) Filed: **Nov. 27, 2019**
